(57) **CLAIM**

The ornamental design for a trigger for spray head, as shown and described.

DESCRIPTION

FIG. 1 is a perspective view of a trigger for spray head; FIG. 2 is a front view of the trigger for spray head shown in FIG. 1;

FIG. 3 is a back view of the trigger for spray head shown in FIG. 1;

FIG. 4 is a right side view of the trigger for spray head shown in FIG. 1;

FIG. 5 is a left side view of the trigger for spray head shown in FIG. 1;

FIG. 6 is a top view of the trigger for spray head shown in FIG. 1; and,

FIG. 7 is a bottom view of the trigger for spray head shown in FIG. 1.

The broken lines depict portions of the trigger for spray head that form no part of the claimed design.

1 Claim, 7 Drawing Sheets
